UNITED STATES PATENT OFFICE.

DANIEL MANSON SUTHERLAND, JR., OF TRENTON, NEW JERSEY, ASSIGNOR TO THE AGASOTE MILLBOARD CO., OF EWING, NEW JERSEY, A CORPORATION OF NEW JERSEY.

SUCTION LIFTING APPARATUS.

1,110,409.

Specification of Letters Patent. Patented Sept. 15, 1914.

Application filed December 20, 1911. Serial No. 666,896.

To all whom it may concern:

Be it known that I, DANIEL MANSON SUTHERLAND, Jr., a subject of the King of Great Britain, and a resident of Trenton, 5 Mercer county, New Jersey, have invented a new and useful Improvement in Suction Lifting Apparatus, of which the following, taken in connection with the accompanying drawings, is a specification.

10 My invention relates to apparatus for holding articles by means of suction and conveying them thus held from one place to another and one of the objects thereof is to produce an apparatus of this kind which is capable of handling articles such as compressed paper pulp in the form of a slab or board.

Another object is to produce such an apparatus which is provided with a plurality 20 of suction elements, each of which is yieldably supported in such manner as to adapt itself automatically to the surfaces of the articles with which it may come into contact in the use of the apparatus.

25 Another object is the provision of an expandible frame for supporting the suction elements whereby the device may be adjusted to adapt it for use in connection with articles of various sizes.

30 Other objects will be pointed out or will otherwise appear in the following description of one form of my invention, shown in the accompanying drawings, in which,

Figure 1 is a plan view of the apparatus, 35 Fig. 2 is a section thereof on the line 2—2 of Fig. 1, Fig. 3 is a section thereof on the line 3—3 of Fig. 1, and Fig. 4 is a sectional detail of one of the suction elements and parts associated therewith.

40 The apparatus illustrated comprises a frame which is suspended from a hoisting device of any suitable kind, a plurality of suction elements supported by said frame and a flexible system of conduits by which 45 said elements are adapted to be connected with a suction pump or other type of exhauster.

The frame comprises a set of transversely

extending, spaced bars 1, which may be the ordinary steel channel bars of commerce, 50 upon which are supported a set of similar, longitudinally extending, spaced bars 2. The transverse bars, are provided with slots at the points of intersection thereof with the longitudinal bars, and the latter are provided with bolt holes at these points. Through the slots and holes bolts 3 or other suitable fastening devices are inserted for holding the bars in their proper positions. By virtue of the pin and slot connection, 60 each of the longitudinal bars may independently be adjusted laterally, and thus, as is obvious, the width of the frame may be adjustably varied. By tightening the fastening devices the parts may be held in their 65 adjusted positions. It is furthermore obvious that the slots may be formed in the longitudinal bars instead of in the transverse bars, in which case the frame would be longitudinally adjustable, or in both bars, 70 in which case the frame would be adjustable both laterally and longitudinally.

Near their central points certain of the transverse bars, are provided with brackets 4, the upper ends of which are secured to a 75 longitudinally extending supporting-rod 5. Tension members 6, each provided with a turnbuckle, connect the outer ends of the transverse members with the centrally disposed brackets thereon. The tension members 80 serve to form trusses whereby the bars are strengthened and prevented from warping or buckling during the use of the lifting apparatus. The supporting rod 5 is provided near its longitudinal center with an 85 eye 7 which is adapted to be engaged by a hook 8 of a hoisting device 8, the latter being of any suitable construction. Upon the operation of the hoisting device, the lifting apparatus balanced thereon with its frame 90 in a substantially horizontal plane, may be raised or lowered as desired. The hoisting and lifting apparatus are adapted to be moved laterally by suitable means (not shown), such as a crane, to which the hoist- 95 ing apparatus is attached.

- The longitudinal frame members are provided at suitable intervals with apertures through which project suction elements, each of which comprises a perforated, saucer-shaped member 9 backed by a disk 10 so as to form a suction chamber there between. Centrally of the disk 10 is secured a pipe 11 which extends upwardly through the aperture in the frame, with which the suction element is associated. Secured to the periphery of the suction element in any suitable manner is a yieldable rim 12 extending slightly below the plane of the lower surface of the perforated member 11. This rim preferably consists of a rubber tube and its function is primarily to form, in an obvious manner, a fluid tight joint between the article lifted or to be lifted and the circumferential portions of the suction element.
- Above the frame each of the pipes 11 is provided with a collar 13 which is secured to its associated pipe by a set screw 14 or any equivalent fastening means. Each frame aperture is of larger diameter than the diameter of its associated pipe 11 so that the suction elements are permitted both to slide freely axially and to have a slight rocking or swinging movement therein. Each collar 13 is of larger diameter than the aperture so that, resting upon those portions of the frame immediately surrounding the aperture, the collar constitutes means whereby the suction element is supported from the frame. The collar may be rounded off on its lower surface so as to offer a minimum resistance to the rocking of the suction element.
- To the upper end of each of the pipes 11 is secured the lower member 15 of a universal joint, within which projects the upper member 16 thereof. A ring 17 screw-threaded to the periphery of the lower member serves to prevent the separation of the upper and lower members. Any suitable type of universal connection may be used but I prefer to use connections of such construction that the members thereof are loosely held so as to have a limited movement toward and from each other and are drawn into proper close relation when the interior of the joint is placed in communication with an exhauster.
- To the upper member of the universal connection is attached a pipe 18 which is connected by flexible, branch connections with the main suction conduit 19. These flexible connections may be of any suitable kind. As shown they comprise a hinge joint 20 of any suitable structure connecting the pipe 18 with the pipe 21 which in turn is connected by a hinge joint 22 to a cross pipe 23, the latter being in communication with the main suction conduit 19.
- The main conduit 19 extends lengthwise of the frame approximately midway be-

tween each pair of suction elements and may be suitably supported by the frame. One end of the conduit 19 is closed by a cap 23 and extends therefrom between the pairs of elements at one side of the frame to the end of the frame, from which point it extends laterally of the frame through a flexible connection comprising hinge joints 24 and pipe sections 25, to a point at the end of the frame between the pairs of elements on the side of the frame opposite to that on which the aforementioned pairs of elements are situated. From this point the conduit 19 extends substantially midway between the second mentioned pairs of elements lengthwise of the frame, and at its end is adapted to be connected by a flexible conduit 26 with an exhauster.

The suction elements of each pair are connected at a common point with the conduit 19 and are therefore connected in parallel while the pairs of suction elements are connected in series. Each element is connected with the main conduit through the intermediary of a flexible connection consisting of the universal joint, the pipes 18, 21 and 23 and the hinge joints 20 and 22. The portions of the conduit 19 on opposite sides of the frame are flexibly connected together by means of the pipe sections 25 and the hinge joints 24.

It is obvious that when the flexible conduit 25 is connected with an exhauster a vacuum, or pressure less than atmospheric pressure, is produced in the conduit 19, the flexible connections and the chambers of the suction elements. Each row of suction elements may be adjusted laterally because of the pin and slot connections between the longitudinal and transverse members of the frame, the flexible connections between the suction elements and the main conduit and between the laterally spaced parallel portions of said main conduit, permitting said adjustment.

The suction lifting apparatus of my invention is particularly adapted for lifting and transporting sheets or boards of compressed pulp such as paper pulp. After compression, preferably by means of a hydraulic press, the boards, which are in practice approximately twelve feet in length, six feet in width and from a quarter of an inch to more than an inch in thickness, are picked up by the lifting apparatus and transported to a device for introducing them into a drying chamber. While being operated upon by the lifter the boards are both ponderous, principally on account of the amount of water which they contain, and frangible. It will readily be understood that the handling of a board of the dimensions and character described is a very delicate operation. Formerly the boards were transported by inserting longitudinal and transverse slats be-

neath each board, the ends of certain of the slats being held and carried by workmen. This crude method not only necessitated the employment of several workmen, but was furthermore very inefficient because it resulted in the frequent breaking or cracking of the boards, thus rendering them useless.

With the device of my invention the boards are expeditiously and efficiently transported without the slightest mutilation of or damage to them. The frame and associated suction elements are lowered so as to rest upon the board by the operation of the crane and hoisting device, and the suction elements are placed in communication with the exhauster by the operation of a suitably positioned valve. The board, as will readily be understood, is thus caused to adhere to the suction elements and may be raised and moved to any desired point by manipulating the control devices for the hoisting device and the crane. The suction device, during these operations, performs the desirable function of removing water from the board.

If any portion of the surface of the board is uneven or disposed at an angle to the horizontal, the particular suction element coming into contact therewith adapts itself automatically to said surface portion because of its flexible, hinged connections with the main suction conduit and of its flexible, slideable and rocking connection with the supporting frame. Both the rocking and the sliding movements of the suction element may cause relative movements between the members of the universal joint and of the hinge joints 20 and 22, and the rocking of the suction element sufficient for all practical purposes, may take place in any axial plane. The rocking of the suction element, as will readily be understood, is facilitated by the employment of a loose universal joint, the members of which may move axially toward each other, leaving a small annular space between them but which are drawn tightly together when placed into communication with the exhauster. The tube 12 assures a tight joint between the board and the suction element even in places where the board surface is irregular or rough.

The size of the supporting frame and consequently the effective area embraced by the suction elements, and the distribution of the several suction elements may be varied in an obvious manner by manipulating the bolts 3 and shifting the longitudinal members of the frame.

60 I claim:

1. A suction lifting apparatus comprising a transportable horizontal frame, a plurality of suction elements, each of said elements being loosely supported by said frame, whereby each element may swing

laterally from the frame in any direction and may move vertically therein, and conduits adapted to connect said elements with an exhauster, substantially as and for the purpose described.

70

2. A suction lifting apparatus comprising a frame having an aperture, a suction element comprising a pipe extending loosely through the aperture in said frame, a main conduit, and a flexible branch conduit connecting said pipe with said main conduit whereby the element may have sliding and rocking movement with respect to the frame, substantially as and for the purpose described.

75

3. A suction lifting apparatus comprising a frame having apertures, a plurality of suction elements each comprising a pipe extending loosely through an aperture in said frame, a main conduit and flexible branch conduits connecting said pipes with said main conduit whereby the elements may each have sliding and rocking movement with respect to the frame, substantially as and for the purpose described.

80

4. A suction lifting apparatus comprising a frame having an aperture therein, a suction element comprising a pipe of smaller diameter than said aperture and extending through said aperture, a collar secured to said pipe above said aperture whereby said element is slidably and swingingly supported by said frame and a flexible connection for placing said element in communication with an exhauster, substantially as and for the purpose described.

90

5. A suction lifting apparatus comprising a frame, a suction element slidably and swingingly supported from said frame, a main suction conduit, a flexible connection comprising a universal joint and a plurality of pipe sections and hinge joints, for connecting said element with said conduit, whereby said element may move axially and swingingly with respect to said frame and said main suction conduit, substantially as and for the purpose described.

105

6. In a suction lifting apparatus, the combination of a frame comprising transversely extending bars and longitudinally extending bars, said bars being connected by pin and slot connections, whereby the size of the frame may be adjustably varied, suction elements supported by said frame, a system of suction conduits adapted to connect said suction elements with an exhauster and means for supporting said frame, substantially as and for the purpose described.

110

7. In a suction lifting apparatus, the combination of a frame comprising transversely extending bars and longitudinally extending bars, suction elements supported by said longitudinally extending bars, and a flexible system of conduits adapted to connect said suction elements with an exhauster, said

120

125

130

bars at their intersections being connected by pin and slot connections; whereby said longitudinally extending bars may be moved laterally to vary the effective area embraced by said suction elements and the distribution thereof, over said area, substantially as and for the purpose described.

In testimony whereof I have hereunto set my hand in the presence of two subscribing witnesses.
